UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

SPOTLIGHT RANGE-LIMITING DEVICE.

Application filed December 29, 1924. Serial No. 753,526.

To all whom it may concern:

Be it known that I, JOHN K. OLSEN, a citizen of the United States, residing in the city of Chicago, in the county of Cook 5 and the State of Illinois, have invented certain new and useful Improvements in Spotlight Range-Limiting Devices, of which the following is a specification, reference being had to the accompanying drawings, forming 10 a part thereof.

The purpose of this invention is to provide an improved mounting for a spotlight or searchlight having means for automatically defeating the illumination of the lamp 15 within predetermined ranges of its vertical and horizontal angular adjustment. It consists in the elements and features of construction shown and described, as indicated in the claims.

20 In the drawings:—

Figure 1 is a top plan view of a searchlight lamp mounted and electrically connected for operating in accordance with this invention.

25 Figure 2 is a section axial with respect to the joint about which the horizontal adjustment is obtained.

Figure 3 is a similar section axial with respect to the joint about which the vertical 30 adjustment is obtained.

Figure 4 is an enlarged detail portion of the section shown in Figure 2.

Figure 5 is a sectional view transaxial 35 with respect to the joint about which vertical adjustment is obtained, showing the lamp in side elevation in full line at horizontal position for projecting a beam forwardly, and in dotted line at three other positions.

40 Figures 6, 7, 8, 9, 10, 11, 12, 13, 14 and 15 are diagrammatic views for showing the course of the lamp-energizing circuit and its interruption at various positions of adjustment of the lamp about the horizontal and 45 vertical axes of the joints respectively.

In the construction shown in the drawings, the lamp body, A, has an axial handle, B, with a laterally projecting stem terminal, B¹. Said stem, B¹, extending horizontally, 50 is vertically pivoted at its right hand end, for adjustment of the lamp through a horizontal angle, to a supporting member, C, which is in turn mounted at its right hand end in a fixed support, D, for swiveling 55 about a horizontal axis to afford adjustment

of the lamp through a vertical angle. At the last mentioned swivel joint the parts which are pivotally related to each other at that joint, viz, the fixed support, D, and the swiveled support, C, have interposed 60 between them around their pivot, two disks, 10 and 11, each formed of insulating material, as bakelite, having embedded in their contacting surfaces,—the left hand surface of the disk, 10, and the right hand surface 65 of the disk, 11,—electrically conductive sectors. These disks are rigid as against relative rotation with the respective members of the joint; that is, the disk, 10, is rigid with the supporting member, D, and the 70 disk, 11, is rigid with the swiveled supporting member, C. The disk, 10, has embedded in its surface facing the disk, 11, for contact therewith, a conductive sector, 12, and the disk, 11 has similarly embedded in its surface for contact with the disk, 10, diametrically opposite angularly narrow electrically conductive sectors, 13 and 23. The joint between the lamp body stem and the supporting member, C, to which it is pivoted for 75 horizontal angular adjustment comprises fork terminals, C¹, C¹¹, of the left hand end of the supporting member, C, and the interposed terminal stem, B¹, of the lamp body handle, B, the pivot bolt, E, extending 80 through the three terminals. Encompassing the pivot bolt between the terminal, B¹, of the stem, and each of the terminals, C¹, C¹¹, there are interposed disks or washers of insulating material, such as bakelite, 85 having embedded in their respectively contacting surfaces sectors of electrically conductive material, viz, two similar disks, 15, 25, rigid as against relative rotation with the terminals, C¹, C¹¹, and disks, 16, 26, secured rigidly as against rotation to the opposite sides of the terminal of the stem, B¹. Embedded in the disks, 15 and 25, at 90 their inner surfaces are metal sectors, 15^a and 25^a, which are respectively at diametrically opposite positions on the two disks which are mounted respectively on the two terminals, C¹, C¹¹.

The disks, 16 and 26 which are mounted 95 on the opposite sides of the terminal of the stem, B¹, have embedded in their outer surfaces facing and contacting the adjacent disks, 15 and 25, respectively, conductive sectors, 16^a and 26^a, being directly opposite each 100 other, so that for the purpose of considering 110

the angular relation of the disks carried by the intermediate member, B¹, of the joint, with respect to the disk carried by the fork terminals, C¹, C¹¹, the two disks, 16 and 26, 5 may be considered as one. From the source of current for energizing the lamp, conventionally indicated as a battery, F, a circuit wire, 30, leads and is connected to the conductive sector, 10^a, of the disk, 10. It will 10 be seen that the circuit becomes branched by the contact of the two conductive sectors of the disk, 11, with the single conductive sector, 10^a, of the disk, 10, and the two branches of the circuit thus shunted in parallel are 15 continued by wires, 32 and 33, from said conductive sectors, 13 and 23, respectively, to the conductive sectors, 15^a, 25^a, embedded in the disks, 15, 25, mounted insulatedly on the fork members, C¹, C¹¹. From the two 20 sectors, 16^a and 26^a, of the disks, 16 and 26, wires, 34, lead and are interlocked and extend as a single conductor to one contact of the lamp, the other contact being grounded as indicated at 40, in the circuit diagrams. 25 Upon considering this structure, it may be understood that at a predetermined position and within a predetermined range of horizontal angular adjustment of the lamp, one of the conductive sectors, 16^a, 26^a, will be out 30 of contact with the adjacent co-operating conductive sector, 15^a or 25^a, so that current cannot pass through the circuit branch which comprises these two conductive elements while it may pass through the corresponding conductive elements at the other 35 side of the joint. And it may be understood that at a certain position within a predetermined range of horizontal angular adjustment of the lamp which is afforded by 40 the joint, D,—hereinafter referred to as the “first” joint,—between the fixed support and the horizontal supporting member, C, one of the conductive sectors, 13 or 23, of the disk, 11, will be out of contact with the conductive sector, 12, of the co-operating disk, 10, and in contact with the insulating area, 10^a, of 45 said disk, while at the same time the other conductive sector, 23 or 13, will be in contact with the conductive sector, 12, so that 50 the current will pass by said first joint through one and not through the other of the branches or shunt paths of the circuit to the other joint, hereinafter called the “second” joint. And it will be seen that if the 55 lamp is adjusted horizontally at said second joint to a position which will cause interruption of the circuit branch which is not interrupted by the coincident adjustment of the lamp at the first joint, the lamp will be 60 extinguished, because the current will be cut off through both paths by which it might reach the lamp. But if, when the parts of the first joint are adjusted for interrupting the left hand branch, leaving the circuit uninterrupted through the right hand branch 65

so far as the first joint is concerned, the parts of the second joint are adjusted for maintaining the circuit through the right hand branch, though the left hand branch be interrupted, there will be no extinguishment of the light, because one branch of the circuit is complete. 70

Upon further consideration and by reference to the wiring diagram, Figures 6, 7 and 8, it may be understood that at the position of the disks indicated in Figure 6, corresponding to the full-line straight-ahead position of the lamp in Figures 1 and 5,—that is, straight-ahead both as to horizontal and vertical adjustment,—the circuit from the battery by the wire, 30, to the conductive sector, 12, is interrupted as to the right hand branch comprising the wire, 32, by contact of the conducting area, 23, with the insulating sector, 10^a, and that the branch through 80 the wire, 33, closed by the contact of 13, with the conducting sector, 12, is interrupted by contact of the insulating sector, 25^b, with the conductive contact, 26^a, so that no current reaches the lamp and illumination is prevented throughout the prohibited angular range both vertical and horizontal. Upon considering wiring diagram, Fig. 7, it may be understood that upon the adjustment of the lamp to the right away from the full-line 85 position Figure 1, to the right hand dotted line position II, shown in that figure to carry the lamp horizontally to the right, beyond the range of prohibited illumination, the circuit will be complete through the wire, 31, from the battery through the first joint by way of the conducting sector, 12, of the disk, 10, making contact with the conducting area, 13, of disk, 11, thence by the wire, 33, to the second joint by way of the conducting area, 25^a, of the left hand disk, 25, of the second joint making contact with the conducting area, 26^a, of the left hand disk, 26. And upon considering Figure 8, it may be understood that upon turning the lamp 90 to the left from the full line position of Figure 1, to the dotted line position III of that figure, the circuit will be closed for illuminating the lamp through the same course as in the right hand adjustment of 95 the lamp, the contact area, 16^a, being merely shifted through the angle of adjustment of the lamp within the angular range of its contact with the secondary contact 15^a, of the right hand disk, 15, of the second joint. 100

Upon considering the wiring diagram of Figure 9, it may be understood that upon the adjustment of the lamp at the first joint away from straight-ahead position which in respect to that adjustment is in horizontal 105 position, the adjustment at the second joint remaining unchanged,—that is, straight ahead, if the vertical adjustment is upwardly through an angle sufficient to carry the lamp beyond the vertical range of pro- 110

- hibited illumination, to dotted line position IV in Figure 5, notwithstanding the lamp is within the prohibited angular range of horizontal adjustment, the circuit will be closed 5 through the wire, 30, from the battery to the contact area, 12, of the disk, 10, making contact with the contact, 23, of the disk, 11, thence by way of the wire, 32, to the contact sector, 15^a, of the right hand disk, 15, of the 10 second joint, then by contact of said sector with the contact, 16^a, of the right hand disk, 16, of said second joint. And by reference to Fig. 10, it will be understood that if the vertical adjustment away from straight 15 ahead position is downwardly to the left from the position shown in full line in Figure 5, to the left-hand dotted line position V in that figure, the lamp is within the prohibited range of horizontal adjustment, it 20 will be illuminated, the circuit being closed through the same course as in the case of the vertical adjustment downward, except that the contact of the contact piece, 13, will be made with the contact sector, 12, at the opposite side of the insulating sector, 12, from that at which this contact was made in the 25 first mentioned vertical adjustment.
- By reference to wiring diagram of Figure 11, it may be understood that if the lamp is 30 adjusted about the first joint for throwing light to the rear dotted line position VI, Fig. 5, within the range of both and horizontal adjustments which is prohibited for forward projection, the circuit will be uninterrupted and the lamp will be illuminated, the 35 circuit being broken as to the right hand branch by the conducting contact, 13, making contact with the insulating sector, 12, at the first joint, but being closed through the 40 left hand branch through contact, 13, wire, 33, and by the contact of the insulating segment, 25^b, with the conducting contact, 26. And by reference to wiring diagram Figs. 12 and 13, it may be understood that if while 45 adjusted for throwing light to the rear, the lamp is turned about the first joint, either up or down beyond the vertical range of prohibited illumination, to dotted line positions indicated by axial lines VII and VIII of 50 Figure 5, the lamp will be illuminated, the circuit being closed from the battery by wire, 30, to the contact sector, 12, making contact with both the conducting contact, 13 and 23, and thence by the wires, 32 and 33, to the 55 conducting area, 15^a and 25^a, of the right and left hand disks, 16^a and 26^a, of the disks, 16 and 26, respectively, of said joint, and by reference to wiring diagram of Figures 14 and 15, it may be understood that if while 60 the lamp is adjusted for throwing a beam to the rear and as to its vertical adjustment is within the range prohibited for forward projection, the lamp is adjusted horizontally about the second joint either to the right or 65 left beyond the prohibited horizontal range of illumination, the lamp will be illuminated and the circuit closed through the first joint by way of the contact, 23, and wire, 33, the conducting sector, 25^a, and conducting contact, 26^a, of the left hand disk, 26, of the 70 second joint.
- Thus it may be seen that the lamp will be automatically extinguished only when coincidentally with adjustment horizontally to within a predetermined range corresponding substantially to the angular extent of the insulating sector, 25^b. It is also adjusted vertically for forward projection of the beam within a predetermined angular range corresponding to the angular extent of the 75 insulating sector, 13; and that, notwithstanding horizontal adjustment to within the first mentioned range, if at the same time the vertical adjustment is not within the second mentioned range, the lamp will continue to 80 be illuminated.
- I claim:—
1. A lamp body and a supporting means for the same comprising a primary stem of the lamp body and a secondary stem on which the primary stem is pivotally supported, and a fixed support on which the secondary stem is pivotally mounted, each of said pivotal joints having about the pivot axis, a plurality of contacting disks comprised in the lamp energizing circuit carried by and insulated from the pivoted parts respectively, and having insulated areas of their respectively contacting surfaces of angular extent and relatively distributed for interrupting the current throughout a predetermined range of angular adjustment; whereby the lamp is automatically extinguished upon its adjustment about both pivots to any position within the 90 ranges respectively predetermined by the angular extent and distribution of said insulated areas. 95
2. In the construction defined in claim 1, foregoing, the lamp energizing circuit being branched and shunted in parallel over the portion extending between the two pivotal junctions by means of providing the disks on the fixed element at each of said junctions with duplicate insulated separated conducting areas, the circuit being branched to said separate conducting areas of said disks at one of said joints, and conductors from the respective conducting areas of the co-operating disks at said joint extending to the duplicate insulated separated conducting areas of the disks of the other joint, the conducting and insulating areas of the disks at either joint being distributed for breaking the circuit through only one branch at any selected adjustment of the parts connected at that joint. 105
3. In the construction defined in claim 1, foregoing, the lamp energizing circuit being branched and shunted in parallel at the por- 110

tion extending between the two pivotal junctions by means of providing one of the contacting disks with two conducting areas angularly separated by insulating areas, circuit conductors from said separated conducting areas respectively, and duplicate pairs of contacting disks at the other joint, said conductors being conducted respectively to conducting areas of the corresponding disks of said pairs, the conducting and insulating areas of the corresponding disks of said pairs being relatively distributed for breaking the circuit through only one branch at any selected adjustment of the parts connected at the last mentioned joint.

5. In the construction defined in claim 1, foregoing, one of said pivotal joints being constructed for adjustment of the movable member at said joint in a horizontal plane, and the other of said joints being constructed for the adjustment of the movable member thereof in a vertical plane, the disks at the first mentioned joint comprising a disk mounted on the fixed member at said joint having two conducting areas angularly separated by insulating area, the co-operating disk at said joint carried by the movable member thereof having a single insulating area of angular extent less than the insulating area, separating the conducting areas of the other disk; the disks at the other joint comprising duplicate pairs at opposite sides of the fixed member at said joint, said fixed member having at its opposite sides, mounted insulately upon it, disks having each

angularly extended insulating and conducting areas; the other disks of the two pairs carried by the moving member at said joint having their conducting areas respectively at opposite sides of the pivot axis of said joint, and conductors from the insulated 35 separated conducting areas of the first joint to said oppositely positioned conducting areas of the respective disks on the moving element at said second joint.

6. In the construction defined in claim 1, 40 the lamp energizing circuit comprising an in-leading line from the current source through the two joints in succession to the lamp, said circuit being branched and shunted in parallel over the portion of its 45 course extending from the first joint to the second; the contact disks at the first joint having their respective insulating and conducting areas distributed and relatively arranged for interrupting the circuit through 50 one of said circuit branches within a predetermined range of angular adjustment of the parts at said first joint, and the disks of the second joint having their respective conducting and insulating areas distributed and 55 relatively arranged for interrupting the circuit throughout the other of said circuit branches within a predetermined range of angular adjustment of the parts of said second joint.

In testimony whereof, I have hereunto set my hand at Chicago, Illinois, this 3 day of December, 1924.

JOHN K. OLSEN.
